DETACHABLE DEVICE FOR AIRING
CLOTHES

Maurice M. Berren, Providence, R. I.

Application May 24, 1940, Serial No. 337,105

8 Claims. (Cl. 211—124)

My invention relates to a detachable device for airing clothes or garments which may also, if desired, be used for drying clothes after being laundered. While my invention may be employed on any type of a house, it is particularly desirable for use in tall apartment houses in large cities where there is no back yard and there is no other available space to air garments.

An object of my invention is to provide a device for airing garments which is completely detachable and which may be readily attached by the tenant in a very short space of time, and which when knocked down takes up a small amount of space for storage purposes.

My invention includes a pair of detachable brackets of the so-called shelf type, each of which is adapted to be secured to the outer surface of a building on each side of a window in horizontally aligned relationship adapted to have a clothes hanger supporting rod detachably mounted on the free ends thereof projecting outwardly from each side of the window.

A further object of my invention is to provide means comprising a clamping rod clamping against the clothes hanger hooks inserted on said clothes hanger supporting rod to prevent gusts of wind from raising the garments and clothes hanger hooks from said supporting rod, preferably also clamping each clothes hanger hook in a set position on said clothes hanger supporting rod against movement axially of said rod.

A further object of my invention is to provide a device which will hold six to twelve average men's and women's garments and provide a maximum amount of airing surface for the airing thereof.

A further feature of my invention is that I provide means including a pair of retaining frames each adapted to abut one end of the group of garments mounted on the clothes hanger supporting rod detachably mountable on said clothes hanger supporting rod exterior of said clothes to prevent the individual garments from swaying individually, and permitting the entire group to gently sway as a compact unit if there is a sufficient wind to sway the combined load of all of the garments.

These and such other objects of my invention as may hereinafter appear will be best understood from a description of the accompanying drawings which illustrate an embodiment thereof.

In the drawings, Fig. 1 is a front elevation showing my device in attached position exterior

of an apartment house window, and having a plurality of garments mounted thereon.

Fig. 2 is an end elevation of the device shown in Fig. 1.

Fig. 3 is a disassembled perspective view of the component parts of my invention.

In the drawings, wherein like characters of reference indicate like parts throughout, 10 generally indicates a detachable device for airing clothes or garments on the outside of a window, constructed in accordance with my invention. Said device includes, in combination, a pair of detachable brackets 12 of the general so-called shelf bracket type, each comprising an L-shaped member having a long arm 14 projecting horizontally outwardly, and a base 16 for detachably mounting said bracket on suitable means projecting laterally from the outer surface of a building on one side of a window in horizontally aligned relationship with the opposite bracket of the pair. While any type of means may be employed for this purpose, I preferably employ the bracket holding plates 18, permanently secured to the window by any suitable means, such as the screws (not shown), said plates having the studs 22 having the enlarged heads 24 and narrower shanks 23 below said heads projecting outwardly therefrom. Each bracket base 16 is provided with the aligned holes 26 to receive the heads 24 of the studs therein, and the slots 28 projecting upwardly in vertical alignment from said holes adapted to receive the narrow shanks 23 of the studs 22 therein, with the heads 24 overlying the portions of the base 16 exterior of said slots 28 to rigidly detachably mount said brackets on the studs 24. Any suitable type of means, however, may be provided to detachably mount the brackets 12 in the proper positions on the window. 40 The type of shelf bracket shown employs an oblique strut 30 attached to the lower end of the bracket base 16 and supporting the horizontal arm of the bracket 14 adjacent the outer end thereof. If desired, the studs 22 may be permanently mounted on the building without the use of a bracket holding plate 18, and if desired, while I preferably employ the detachable brackets 12, each bracket may, if desired, be permanently mounted in its proper position on each side of the window.

I provide means detachably securable to the outer ends of each bracket to extend horizontally between the outer ends of said brackets for holding the hooks 36 of a plurality of clothes hangers 34 thereon. In my preferred embodiment

ment said means comprises the clothes hanger supporting rod 32 detachably mountable on the free ends of said detachable brackets 12. I also preferably employ a clamping rod 38 also detachably mounted on the free ends of said brackets, in the preferred embodiment over the hooks 36 of said clothes hangers 34 clamping said clothes hanger hooks 36 on said clothes hanger supporting rod 32, although it is apparent that any other suitable type of means for preventing the hooks 36 from being lifted off of the supporting rod 32 may be employed.

While any suitable type of means may be employed for detachably mounting the clothes hanger supporting rod 32 on the free ends of said brackets 12 and the clamping rod 38 in superimposed clamping relationship thereon, in the preferred embodiment said means is preferably constructed as follows: One of said brackets in the embodiment shown, the bracket 12^a has the threaded holding stud 40 projecting upwardly from the outer free end thereof. The other of said brackets, in the embodiment shown, the bracket 12^b has a duplex rod holding loop 42 projecting upwardly from the outer end thereof, in the embodiment shown comprising the end portion of the arm 14 integrally bent up in the form of said duplex loop of a shape to hold the ends of the two rods, one superimposed above the other. If desired, a threaded adjustable clamping bolt 43 may be adjustably mounted in a threaded hole 45 in the upper end of said loop 42.

In the embodiment shown, the clothes hanger supporting rod 32 and the clamping rod 38 are preferably of substantially similar shape, and of substantially similar size, each having a free end 44 and 46 respectively engageable within the duplex rod holding loop 42 and the holes 48 and 50 in the enlarged opposite end thereof for receiving said threaded stud 40 therethrough.

To assemble the portion of the device heretofore described, each bracket 12^a and 12^b is detachably mounted on their respective studs 22 in the manner described. The free end 44 of the garment supporting rod 32 is inserted within the duplex loop 42 and the opposite end lowered so that the stud 40 projects through the hole 48 thereof. The hooks 36 of the clothes hangers 34 having the respective garments 52 mounted thereon are then hung on the clothes hanger supporting rod 32. The end 46 of the clamping rod 38 is then inserted within the duplex rod holding loop 42 over the then inserted end 44 of the clothes hanger supporting rod 32 and the opposite end of said clamping rod is then lowered so that the threaded holding stud 40 projects through the hole 50 therein. The clamping nut 54 is then inserted on the upper end of the threaded stud 40 and threaded thereon until the clamping rod 38 is brought into the desired position above the hooks 36. If desired, the duplex loop 42 may be of such a size, and the nut 54 only so tightly threaded onto said stud 40, that the clamping rod 38 merely prevents the hooks 36 from being lifted off the clothes hanger supporting rod 32, but if desired, the duplex loop 42 may be of such a size, or the adjustable bolt 43 lowered to abut the clamping rod 38, or the nut 54 may be threaded so tightly onto the threaded stud 40 that the clamping rod will abut the clothes hanger hooks 36 to positively clamp each of them in a set non-slidable position against said clothes hanger supporting rod. If desired, a loop similar to the loop 42 with its respective adjustable clamping bolt 43 may be

employed on the free end of the bracket 12^a in place of the threaded stud 40 and adjusting nut 54, in which case the enlarged ends with their respective holes 48 and 50 in the clothes hanger supporting rod 32 and the clamping rod 38 may be omitted.

I also provide means to prevent the garments from being blown individually on or off the garment hangers 34 and compelling all said garments to gently sway as a unit in a gust of wind. In the preferred embodiment, said means comprises a pair of retaining frames 56, each adapted to abut one end of a group of garments 52 supported on the clothes hangers 34 mounted on said clothes hanger supporting rod 32, detachably mounted on said clothes hanger supporting rod 32 exterior of said garments, the frame 56^a abutting the end of the garments adjacent the bracket 12^a and the frame 56^b abutting the end of the garments adjacent the bracket 12^b, and I may, if desired, employ a retaining frame spacer and retaining bar 58 having each end thereof detachably securable to one of said frames. In the embodiment shown, each of said frames 56^a and 56^b comprises a triangle formed of bent wire and having a loop 60 at the apex thereof for threading on the clothes hanger supporting rod 32 and terminating in the spaced ends 62 in the base 64 thereof, forming the space 66 between said spaced ends. The spacing and retaining bar 58 is provided with the loop 68^a at one end thereof and the loop 68^b at the opposite end thereof, each detachably securable to one of said wire frames 56^a and 56^b through the space 66 between the spaced ends 62 in the base 64 thereof. Where the retaining frames 56^a and 56^b are employed, the loop 60 of the frame 56^a is inserted on the garment hanger supporting rod 32 close to the end having the hole 48 therein. The clothes hangers 34 having the garments 52 mounted thereon are then hung on the clothes hanger supporting rod 32. The loop 60 of the other frame 56^b is then threaded on the clothes hanger retaining rod 32 adjacent the free end 44 thereof. The loops 68^a and 68^b of the retaining bar 58 are then suitably inserted in said retaining frames 56^a and 56^b by bringing them first in the space 66 between the free ends 62 of the bent wire and moving them forwards to receive the front end of the respective base of each respective frame 56^a and 56^b. The device is then clamped into position in the manner previously explained.

As shown in Fig. 1, my device may be conveniently mounted from one-half to two-thirds the distance from the lower end of the lower window sash 70, of the window 72. This provides a readily accessible place from within the building for hanging and removing the garments and device.

While, as stated, I preferably employ the supporting brackets 12 of a type which may be detachably secured at the will of the user, it is apparent that if desired, the brackets 12 may when once attached be permanently affixed to the building. In the claims I employ the words "adapted to be attached" to cover the device whether in attached or detached position.

It is apparent that I have provided a novel type of a detachable device for airing garments on the outside of a window with the advantages explained above.

It is understood that my invention is not limited to the specific embodiment shown and that various deviations may be made therefrom.

without departing from the spirit and scope of the appended claims.

What I claim is:

1. A detachable device for airing clothes on the outside of a window, comprising, in combination, a pair of shelf brackets, adapted to be secured to the outer surface of a building on opposite sides of a window in horizontally aligned relationship, one of said brackets having a threaded holding stud projecting upwardly from the outer end thereof, and the other of said brackets having a duplex rod holding loop projecting upwardly from the outer end thereof, two rods of similar shape, each having a free end engageable within said loop and a hole on the opposite end for receiving said threaded stud, one comprising a clothes hanger supporting rod and the other comprising a clamping rod for clamping against clothes hanger hooks inserted on said clothes hanger supporting rod, and a clamping nut threadable on said stud over the holes in said rods, a pair of retaining frames each adapted to abut one end of a group of garments mounted on clothes hangers supported on said clothes hanger supporting rod, detachably mounted on said clothes hanger supporting rod exterior of said clothes, each of said frames comprising a triangle formed of bent wire having a loop for threading on said clothes hanger supporting rod at the apex thereof and terminating in spaced ends in the base thereof, and a retaining frame spacer and retaining bar having a loop at each end thereof detachably securable to one of said wire frames through the space between the spaced wire ends in the base thereof.

2. A detachable device for airing clothes on the outside of a window, comprising, in combination, a pair of shelf brackets, adapted to be secured to the outer surface of a building on opposite sides of a window in horizontally aligned relationship, a clothes hanger supporting rod detachably mountable on the free ends of said detachable brackets for receiving the hooks of a plurality of clothes hangers having garments thereon, a clamping rod also detachably mountable on the free ends of said brackets for clamping said clothes hanger hooks on said clothes hanger supporting rod, a pair of retaining frames each adapted to abut one end of a group of garments mounted on clothes hangers supported on said clothes hanger supporting rod, detachably mounted on said clothes hanger supporting rod exterior of said clothes, each of said frames comprising a triangle formed of bent wire having a loop for threading on said clothes hanger supporting rod at the apex thereof and terminating in spaced ends in the base thereof and a retaining frame spacer and retaining bar having a loop at each end thereof detachably securable to one of said wire frames through the space between the spaced wire ends in the base thereof.

3. A detachable device for airing clothes on the outside of a window, comprising, in combination, a pair of shelf brackets, adapted to be secured to the outer surface of a building on opposite sides of a window in horizontally aligned relationship, a clothes hanger supporting rod detachably mountable on the free ends of said detachable brackets for receiving the hooks of a plurality of clothes hangers having garments thereon, a clamping rod also detachably mountable on the free ends of said brackets for clamping said clothes hanger hooks on said clothes hanger supporting rod, a pair of retaining frames each adapted to abut one end of a group of gar-

ments mounted on clothes hangers supported on said clothes hanger supporting rod, detachably mounted on said clothes hanger supporting rod exterior of said clothes, and a retaining frame spacer and retaining bar detachably securable to each of said retaining frames.

4. A detachable device for airing clothes on the outside of a window, comprising, in combination, a pair of shelf brackets, adapted to be secured to the outer surface of a building on opposite sides of a window in horizontally aligned relationship, one of said brackets having a threaded holding stud projecting upwardly from the outer end thereof, and the other of said brackets having a duplex rod holding loop projecting upwardly from the outer end thereof, and two rods of similar shape, each having a free end engageable within said loop and a hole on the opposite end for receiving said threaded stud, one comprising a clothes hanger supporting rod and the other comprising a clamping rod for clamping against clothes hanger hooks inserted on said clothes hanger supporting rod.

5. A detachable device for airing clothes on the outside of a window, comprising, in combination, a pair of shelf brackets, adapted to be secured to the outer surface of a building on opposite sides of a window in horizontally aligned relationship, at least one of said brackets having a duplex rod holding loop projecting upwardly from the outer end thereof, and having a threaded hole in the upper end thereof, two rods of similar shape, each having an end engageable within said loop, one comprising a clothes hanger supporting rod and the other comprising a clamping rod for clamping against clothes hanger hooks inserted on said clothes hanger supporting rod, and an adjustable bolt threaded within said threaded loop hole to abut said clamping rod for adjustably clamping said clamping rod in clamping position.

6. A detachable device for airing clothes on the outside of a window, comprising, in combination, a pair of shelf brackets, adapted to be secured to the outer surface of a building on opposite sides of a window in horizontally aligned relationship, at least one of said brackets having a duplex rod holding loop projecting from the outer end thereof, two rods of similar shape, each having an end engageable within said loop, one comprising a clothes hanger supporting rod and the other comprising a clamping rod for clamping against clothes hanger hooks inserted on said clothes hanger supporting rod, and means to adjustably clamp said clamping rod in clamping position.

7. A detachable device for airing clothes on the outside of a window, comprising, in combination, a pair of shelf brackets, adapted to be secured to the outer surface of a building on opposite sides of a window in horizontally aligned relationship, a clothes hanger supporting rod detachably mountable on the free ends of said brackets for receiving the hooks of a plurality of clothes hangers having garments thereon, a pair of retaining frames each adapted to abut one end of a group of garments mounted on clothes hangers supported on said clothes hanger supporting rod, detachably mounted on said clothes hanger supporting rod exterior of said clothes, each of said frames comprising a triangle formed of bent wire having a loop for threading on said clothes hanger supporting rod at the apex thereof and terminating in spaced ends in the base thereof and a retaining frame

spacer and retaining bar having a loop at each end thereof detachably securable to one of said wire frames through the space between the spaced wire ends in the base thereof.

8. A detachable device for airing clothes on the outside of a window, comprising, in combination, a pair of shelf brackets, adapted to be secured to the outer surface of a building on opposite sides of a window in horizontally aligned relationship, a clothes hanger supporting rod detachably mountable on the free ends of

said brackets for receiving the hooks of a plurality of clothes hangers having garments thereon, a pair of retaining frames each adapted to abut one end of a group of garments mounted on clothes hangers supported on said clothes hanger supporting rod, detachably mounted on said clothes hanger supporting rod exterior of said clothes, and a retaining frame spacer and retaining bar detachably securable to each of said retaining frames.

MAURICE M. BERREN.
